UNITED STATES PATENT OFFICE

172,201

COMBINED CHAIR AND HASSOCK

Wilford Staveley, Gardner, Mass.

Application May 19, 1953, Serial No. 25,107

Term of patent 7 years

(Cl. D15—1)

To all whom it may concern:

Be it known that Wilford Staveley, a citizen of the United States, residing at Gardner, in the county of Worcester and State of Massachusetts, has invented a new, original, and ornamental Design for a Combined Chair and Hassock, of which the following is a specification, reference being had to the accompanying drawing, forming part thereof.

Fig. 1 is a top plan view of a combined chair and hassock with the backrest in lowered position, showing my new design;

Fig. 2 is a view in front elevation thereof; and

Fig. 3 is a view in side elevation, showing the back rest raised.

I claim:

The ornamental design for a combined chair and hassock, as shown.
